UNITED STATES PATENT OFFICE.

WALTER L. FUNK, OF GRAND RAPIDS, MICHIGAN.

SUSPENDERS.

Application filed December 14, 1921. Serial No. 522,319.

To all whom it may concern:

Be it known that I, WALTER L. FUNK, a citizen of the United States, residing at Grand Rapids, in the county of Kent and 5 State of Michigan, have invented certain new and useful Improvements in Suspenders, of which the following is a specification.

My invention relates to improvements in gentlemen's suspenders, and more particularly to suspenders in use for supporting overalls and like garments, and it has for its objects, first, to provide a means whereby a flat helical spring may be used to produce resiliency at the ends of the suspenders independently of the elasticity in the fabric from which the body of the suspender is made; second, to provide a means whereby the use of sheet metal strips for connecting the button straps of suspenders with the 15 resilient element may be dispensed with; third to provide a means whereby the pressure at the lower end of the resilient element may be properly distributed across the bearing or supporting part of the suspender.

I attain these objects by the peculiar distribution and operation of the several elements shown in the accompanying drawing, in which Fig. 1 is an elevation of the 20 end of a suspender with the side removed to disclose the application of my improvements. Fig. 2 is an edge elevation of the same with both folds of the end of the suspender in place and the resilient element 25 between them. Fig. 3 is an elevation of the end of a suspender, with a modified form of strap connection as it appears when properly assembled. Fig. 4 shows the application of a modified form of button strap. 30 Fig. 5 shows still another modified form of strap, the two latter figures being given simply to show that different forms of straps may be used with my invention without departing from the fundamental object 35 of the invention. Fig. 6 is in elevation of the end of a suspender unfolded to show the slot through which the button straps are passed. Fig. 7 is a view similar to Fig. 6 showing two slots for use with the straps 40 shown in Fig. 4. Fig. 8 is an elevation of the lower plate with a lip extending downwardly thereon for forming the hook shown in Fig. 10. Fig. 9 is the same plate without the downwardly extending lip, and Fig. 10 is 45 an edge view of Fig. 8 with the downwardly

extending lip formed into a hook to be used as hereinafter described.

Similar reference characters indicate similar parts throughout the several views.

In the construction of these suspenders 60 I use ordinary, inelastic, webbing for the body 1, and form slots, as indicated at *d*, upon the line where the lower part, 1', folds upon the body, forming a pocket into which the resilient element, or spring 2, and its 65 connected elements are mounted. For the button straps 3 I use some very flexible or pliable material, as raw hide, or its equivalent, and so form the upper end at 4 that it may be drawn downwardly without danger of becoming disconnected from the upper end of the spring 2. The lower end, 6, of the button strap 3 is made integral with the upper, or body portion and passes downwardly through the slot *d*, as indicated in 70 Figs 1 and 2. This leaves the upper ends of the straps 3 free to move upwardly or downwardly as strain is brought to bear upon, or is released from the straps.

To make the flat coiled springs 2 available for use with very flexible straps, passing through the entire length of the spring and secured at their upper ends to the upper end of the spring, I find it necessary to provide a supporting element for the 85 lower end of the spring, and for this purpose I use a short metal plate 5 that extends upwardly into the lower end of the spring and is provided with laterally extending integral arms, *a*, so positioned that they 90 will rest between the folds of the end of the suspender and the lower end of the spring, at each edge of the spring and at each side of the opening *d* in the suspender. This plate may be made much more serv- 95 iceable by forming a hook *b* upon its lower end below the line *x*—*x*, that may be passed through the opening *d* and hook over the end of the suspender, as indicated in Fig. 2, and thus avert the danger of the plate 5 being drawn upwardly within the folds of 100 the suspender.

In Fig. 3 I have shown the lower end of the strap 3, at 3', folded over and secured at *e* to form a loop for the reception and 105 proper action of the modified form of button loop shown as 6'. In Fig. 5 I have shown this strap at 3² arranged to support the modified button loops 6², as at *e* in said figure, and in Fig. 4 I have shown still an- 110

other modification of the button straps and loops as indicated at 6³, demonstrating that my appliance may be used with any form of button loop without departing from the spirit of my invention, or making any modifications whatever therein.

Having thus fully described my invention, what I claim as new in the art, is:

1. In combination with the folded ends 10 of a suspender having openings there-through, a flat coiled spring mounted within said fold, a broad, thin, button hole strap passed through lengthwise of the spring with its upper end secured to the upper end 15 of the spring, and a metal plate extended

upwardly into the spring parallel with the button hole strap and having laterally extended integral arms thereon and positioned between the end of the spring and the fold of the suspender.

2. In combination with the elements covered in claim 1, a hook formed upon the lower end of the metal plate and passing through the opening in the end of the suspender and upwardly upon the outside of 25 the suspender fold.

Signed at Grand Rapids, Michigan, December 9th, 1921.

WALTER L. FUNK.
